CLAIM

The ornamental design for a domestic scale weight display module, as shown and described.

DESCRIPTION

FIG. 1 is a top plan view of a domestic scale weight display module showing our new design;

FIG. 2 is a front elevational view thereof;

FIG. 3 is a right side elevational view thereof, the left side being a mirror image thereto;

FIG. 4 is a bottom plan view thereof; and,

FIG. 5 is a rear elevational view thereof.
